GEORGE F. STEEDMAN, OF ST. LOUIS, MISSOURI, ASSIGNOR TO CURTIS & COMPANY MANUFACTURING COMPANY, OF WELLSTON, MISSOURI, A CORPORATION OF MISSOURI.

LUBRICATING APPARATUS FOR COMPRESSORS AND SIMILAR MACHINES.

1,162,262.

Specification of Letters Patent. Patented Nov. 30, 1915.

Application filed June 21, 1915. Serial No. 35,816.

To all whom it may concern:

Be it known that I, GEORGE F. STEEDMAN, a citizen of the United States, residing at St. Louis, Missouri, have invented a certain new and useful Improvement in Lubricating Apparatus for Compressors and Similar Machines, of which the following is a full, clear, and exact description, such as will enable others skilled in the art to which it applies to make and use the same.

This invention relates to machines of the type in which lubricating oil is supplied to a vertically-disposed cylinder and to certain bearings and parts arranged inside of the crank case of the machine, by means of oil-throwing devices that dip into a bath of oil in the crank case when the machine or engine is in operation.

The main object of my present invention is to provide an efficient lubricating system of simple construction, which is so designed that it is not necessary to use a baffle plate at the lower end of the cylinder of the machine, in order to prevent an excessive supply of oil to the cylinder.

Another object is to provide an inexpensive lubricating apparatus for machines of the general type mentioned that comprises means for supplying a definite quantity of oil to the parts of the machine which it is desired to lubricate and means for conducting substantially all of the surplus oil not required by said parts back to the oil bath in the crank case, the apparatus being so designed that it is not necessary to continually adjust same to compensate for slight variations in the speed of the machine, in the depth of the oil bath and in the viscosity of the oil.

Other objects and desirable features of my invention will be hereinafter pointed out.

Figure 1 of the drawings is a side elevational view, partly in vertical section, of a single cylinder compressor constructed in accordance with my invention. Fig. 2 is a vertical sectional view taken on the line 2—2 of Fig. 1; and Fig. 3 is a horizontal sectional view taken on the line 3—3 of Fig. 2.

Referring to the drawings, which illustrate the preferred form of my invention, A designates the cylinder of the machine, B the piston in said cylinder, C the crank

case, D the crank shaft and E the connecting rod which joins the piston to the crank arm F on the crank shaft, the cylinder A being arranged vertically with its open lower end communicating with the crank case. The bottom portion of the crank case C acts as a container for a bath of lubricating oil (not shown) and the crank arm on the crank shaft is provided with a pair of oil-throwing devices 1 and 1^a that are arranged out of vertical alinement with the cylinder and which are adapted to dip into the bath of oil and throw the oil in vertical planes, said oil throwers being preferably provided with knife-pointed ends so that they will throw small drops of oil in well defined paths which vary only slightly in reasonable speed limits. The oil that is thrown upwardly by the oil throwers 1 and 1^a is caught by devices which conduct the oil to the crank shaft bearings 2, to the connecting rod bearing 3 and to the coöperating surfaces of the piston and cylinder, and means are provided for conveying substantially all of the surplus oil not required by said lubricated parts back to the oil bath in the crank case. In the preferred form of my invention as herein shown the oil thrower 1 supplies oil to a cylinder lubricating device 4 which consists of an inclined pin arranged at the upper end of the crank case in vertical alinement with the oil thrower 1, so that it will intercept some of the oil thrown upwardly by the device 1. The pin 4 inclines downwardly, as shown in Fig. 1, and the lower end of same projects into an opening 5 formed in the lower end of the cylinder A, said pin being preferably carried by a plug 6 that is screwed into the outer wall of a pocket 7 formed in the crank case at a point above the lower end of the cylinder A. Some of the oil that is thrown upwardly by the oil thrower 1 is caught by the pin 4 and conducted to the inner wall of the cylinder A, the reciprocating movement of the piston B in said cylinder causing the oil to be distributed over the coöperating surfaces of the piston and cylinder, and thus keeping the cylinder and piston thoroughly lubricated.

The wrist pin 8 that secures the connecting rod E to the piston is kept lubricated by means of ducts 8^a in the piston that lead

from the wrist pin bearings and terminate in the outer face of the piston, as shown in Fig. 1. The inclined pin 4 that lubricates the cylinder is preferably made circular-shaped in cross section, and if said pin is properly designed or made the proper diameter, it will intercept the approximately correct amount of oil and supply it to the cylinder to keep the cylinder and piston properly lubricated. The number of drops of oil required per minute in a given cylinder at a given number of revolutions per minute does not have to be exact, and I have found that a cylinder lubricating device consisting of an inclined pin of fixed diameter will give the proper amount of oil within good commercial limits for a commercial variation in the speed of the machine accompanied by a commercial variation in the oil bath and also a commercial variation in the viscosity of the oil.

A vertically-disposed web or vane 9 that extends transversely across the lower end of the pocket 7 in vertical alinement with one of the crank shaft bearings 2 intercepts some of the oil thrown upwardly by the oil thrower 1 and conducts such oil to the vertical end wall of the crank case down which the oil, drains to the coöperating crank shaft bearing 2, the lower edge of said vane or web being inclined downwardly toward the vertical end wall of the crank case, as shown in Fig. 1. A similar web or vane 9^a is arranged at the opposite end of the crank case in vertical alinement with the oil thrower 1^a, so as to intercept some of the oil thrown upwardly by the device 1^a and conduct it to the other crank shaft bearing 2 in a similar manner. If desired, the end walls of the crank case can be provided with inwardly-projecting ribs 10 and 10^a that are arranged over the crank shaft bearings 2, as shown in Fig. 1, and which are provided with holes 11, as shown in Fig. 2, that receive and hold the oil which drains down the end walls of the crank case, each of said ribs being of substantially inverted V-shape, so that the surplus oil which overflows from the oil pocket 11 formed in said rib will be conducted back to the oil bath in the crank case.

The connecting rod bearing 3 is provided with an oil holder or reservoir 12 which is supplied with oil by means of oil-dripping devices 13 consisting of inclined ribs arranged on the inner side of the crank case adjacent the upper end of same in alinement with the path of travel of the connecting rod bearing 3. Oil is conducted to these oil-dripping devices 13 by means of oil-distributing flanges 14 and 14^a arranged at the upper end of the crank case in such a manner that they will intercept some of the oil that is thrown upwardly by the oil throwers on the crank arm, the distributing

flanges 14 extending from one of the end walls of the crank case to the oil-dripping devices 13, as shown in Fig. 3, and having inclined lower edges over which the oil travels to the devices 13, the distributing flanges 14^a terminating at the lower end of the cylinder instead of running to the end wall of the crank case, so that they will not intercept the oil that is thrown upwardly into the pocket 7 in which the lubricating device 4 is arranged.

The oil-throwing devices and the coöperating oil-intercepting members and oil-distributing and feeding devices previously mentioned are so proportioned and designed that approximately the proper amount of oil will be supplied to the cylinder, to the crank shaft bearings and to the connecting rod bearing to keep said parts thoroughly lubricated under normal working conditions, but, in order to prevent an objectionable quantity of any surplus oil not required by the connecting rod bearing or which may be thrown from the crank arms from being thrown into the open lower end of the cylinder when the machine is in operation, I have provided means for collecting said surplus oil thrown centrifugally from the oil reservoir 12 of the connecting rod bearing or the crank arms F, and conducting said surplus oil back to the crank case. In the form of my invention herein shown said means consists of two substantially yoke-shaped deflectors 15 arranged at the upper end of the crank case in vertical alinement with the path of travel of the connecting rod bearing 3, as shown in Figs. 1 and 3. When the machine is in operation substantially all of the oil that is thrown centrifugally from the crank arm or from the reservoir 12 will be caught by the deflectors 15 and conveyed to the side walls of the crank case, down which such oil drains to the oil bath in the bottom of the crank case.

From the foregoing it will be seen that the oil-throwing devices 1 and 1^a supply a definite quantity of oil to the cylinder lubricating device 4, to the oil holders 11 for the crank shaft bearings and to the dripping devices 13 which feed the oil reservoir of the connecting rod bearing 3. Any surplus oil not required by the crank shaft bearings is conducted back to the oil bath by the inclined flanges 10 and 10^a on the end walls of the crank case, and an objectionable quantity of any surplus oil not required by the connecting rod bearing or any oil that is thrown centrifugally by the crank arm is conducted back to the oil bath by the U-shaped or yoke-shaped deflectors 15 arranged at the upper end of the crank case.

The oil that constitutes the oil bath is introduced into the crank case through a filling device 16 of any preferred design, and a breather opening 17 is formed in one

of the end walls of the crank case, as shown in Fig. 1. In order to prevent the oil from escaping from the crank shaft bearings 2, I have provided one of said bearings on its underside with an inclined rib 18, as shown in Fig. 1, which is so arranged that any oil that leaks out of the crank shaft bearing 2 with which it co-operates will be led back to the crank case. The outer end of the other 10 crank shaft bearing 2 terminates in proximity to an oil-collecting pocket 19, from which a duct 20 leads to the crank case, so that any oil that escapes from the outer end of said crank shaft bearing 2 will be conducted back to the crank case.

15 A lubricating system of the construction above described is efficient, is of simple construction and it can be manufactured at a low cost. It is so designed that it is not necessary to use a baffle plate at the lower 20 end of the cylinder, in order to prevent an excessive supply of oil to the cylinder, and it is so designed that it is not necessary to constantly change the adjustment of same to 25 provide for slight variations in the speed of the machine, in the depth of the oil bath and in the thickness of the oil.

The devices that conduct the oil from the bath to the feeding and distributing devices 30 are so designed and arranged that they throw small drops of oil in well defined paths which vary only slightly in reasonable speed limits, and said feeding and distributing devices are so designed and arranged 35 that the oil they intercept will be conveyed to the parts of the machine which require lubrication. All, or practically all, oil that is thrown unintentionally by the crank arm or other moving parts in the crank case is 40 caught by the deflectors 15 and conducted back to the oil bath. Consequently, said deflectors make it possible to supply the cylinder and other parts with a definite quantity of oil by means of the throwing 45 devices and the distributing devices with which they co-operate, the surplus oil or oil that is thrown unintentionally being prevented from entering the cylinder or dripping onto the oil-distributing devices by 50 means of the deflectors 15.

Having thus described my invention, what I claim, and desire to secure by Letters Patent, is:

1. In a machine of the character described, 55 a crank case, a vertically-disposed cylinder having its lower end open and in communication with said crank case, an oil distributing means, a crank shaft provided with an oil-throwing means that co-operates with said 60 distributing means to supply a definite quantity of oil to certain parts of the machine that require lubrication; and deflectors arranged in the crank case in proximity to the open lower end of the cylinder without obstructing same for preventing surplus oil

from being thrown by the moving parts of the machine into the cylinder.

2. In a machine of the character described, 70 a crank case, a vertically-disposed cylinder whose lower end is open and in communication with the crank case, oil-distributing devices for supplying oil to certain parts of the machine which require lubrication, a crank shaft provided with means that dips into a bath of oil and throws the oil onto 75 said devices, and means for collecting any surplus oil that is thrown by moving parts in the crank case and preventing such oil from finding its way in objectionable quantities to the parts which said distributing 80 devices supply with oil.

3. In a machine of the character described, 85 a cylinder having its lower end open and in communication with a crank case that contains a bath of lubricating oil, oil-distributing devices that supply oil to the cylinder and other parts of the machine that require lubrication, a revolving means in the crank case that dips into said bath and throws oil directly onto said distributing devices, and 90 means for preventing an objectionable quantity of thrown oil from striking said oil-distributing devices or from entering the open end of the cylinder.

4. In a machine of the character described, 95 a crank case that is adapted to contain a bath of lubricating oil, a vertically-disposed cylinder having its lower end open and in communication with the crank case, a revolving oil-throwing means in the crank 100 case that is adapted to dip into the bath of oil in the crank case and supply oil to parts of the machine that require lubrication, and a deflector arranged in the upper portion of the crank case at one side of the cylinder 105 for preventing an objectionable quantity of oil from being thrown directly into the lower end of the cylinder.

5. In a machine of the character described, 110 a crank case that is adapted to contain a bath of lubricating oil, a vertically-disposed cylinder having its lower end open and in communication with the crank case, a revolving oil-throwing means in the crank case that is adapted to dip into the bath of oil in the 115 crank case and supply oil to parts of the machine that require lubrication, and a deflector arranged in the upper portion of the crank case at one side of the cylinder for preventing oil in objectionable quantities 120 from being thrown directly into the lower end of the cylinder, said deflector being so designed that it will conduct the oil which it intercepts back to the oil bath.

6. In a machine of the character described, 125 a crank case that is adapted to contain a bath of lubricating oil, a vertically-disposed cylinder having its lower end open and in communication with said crank case, a crank shaft provided with an oil-throwing means 130

that dips into said bath of oil intermittently and throws drops of oil upwardly, and yoke-shaped deflectors arranged at the upper end of the crank case in vertical alignment with the path of travel of the crank arm on the crank shaft for preventing an objectionable quantity of oil from being thrown into the open end of the cylinder.

7. In a machine of the character described, 10 a crank case that is adapted to contain a bath of lubricating oil, a vertically-disposed cylinder having its lower end open and in communication with said crank case, a crank shaft having a crank arm connected by 15 means of a connecting rod with a piston in said cylinder, an oil-dripping device on the side wall of the crank case arranged in alignment with the path of travel of said connecting rod for supplying oil to the bearing of same, and means for delivering oil from 20 said oil bath onto said dripping device.

8. In a machine of the character described, 25 a crank case, a vertically-disposed cylinder arranged at the upper end of the crank case and having an opening formed in the lower portion of the side wall of same, a downwardly-inclined oil feeding device projecting into said opening, and a revolving oil-throwing means in the crank case for supplying oil to said device.

9. In a machine of the character described, 30 a crank case that is adapted to contain a bath of lubricating oil, a vertically-disposed cylinder arranged in the upper end of said crank case and having an opening formed in its side wall adjacent the lower end of same, a cylinder-feeding device arranged in a pocket or housing that communicates with the crank case, said device consisting of a downwardly-inclined pin that projects into the opening in the side wall of the cylinder, and means operated by the crank shaft of the machine that dips into said bath of oil and throws drops of oil upwardly onto 45 said pin.

10. In a machine of the character described, 50 a crank case that is adapted to contain a bath of lubricating oil, a vertically-disposed cylinder having its lower end open and in communication with the crank case, means for throwing drops of oil in well defined vertical paths when the machine is in 55 operation, means for intercepting said thrown oil and conducting it to the parts of the machine that require lubrication, and means for causing the surplus oil not required by said lubricated parts to pass back to the oil bath without coming in contact with said oil-intercepting means.

60 11. In a machine of the character described, 65 a crank case having a pocket at the upper end of same, a vertically-disposed cylinder whose lower end forms one wall of said pocket, said wall having an opening

therein, a removable, downwardly-inclined 6. pin in said pocket that projects into said opening, and means for throwing drops of oil onto said pin when the machine is in operation.

12. In a machine of the character de- 70 scribed, a crank case that is adapted to contain a bath of lubricating oil, a crank shaft mounted in bearings that are supported by the end walls of the crank case, oil-throwing devices actuated by the crank shaft, means 75 for intercepting some of the oil thrown by said devices and conducting it to the end walls of the crank case down which it drains, substantially arc-shaped flanges on the end walls of the crank case arranged above said 80 crank shaft bearings, and pockets in said flanges for receiving the oil that drains down the end walls of the crank case.

13. In a machine of the character de- 85 scribed, a crank case that is adapted to contain a bath of lubricating oil, a vertically-disposed cylinder at the upper end of said crank case, a crank shaft and a connecting rod for joining the crank arm thereon to a piston in said cylinder, oil-dripping de- 90 vices on the side walls of the crank case for supplying oil to the bearing of said connecting rod, oil-intercepting devices arranged at the upper end of the crank case for conducting oil to the bearings of the crank shaft, 95 and an oil-throwing means actuated by the crank shaft that supplies oil to said dripping devices and oil-intercepting devices.

14. In a machine of the character de- 100 scribed, a crank case that is adapted to contain a bath of lubricating oil, a vertically-disposed cylinder, at the upper end of said crank case, a crank shaft and a connecting rod for joining the crank arm thereon to the piston in said cylinder, oil-dripping devices 105 on the side walls of the crank case for supplying oil to the bearing of said connecting rod, oil-intercepting devices arranged at the upper end of the crank case for conducting oil to the bearings of the crank shaft, an oil- 110 throwing means actuated by the crank shaft that supplies oil to said dripping devices and oil-intercepting devices, a cylinder lubricator which is supplied with oil by said oil-throwing means, and deflectors arranged 115 on opposite sides of the cylinder in vertical alignment with the path of travel of the crank arm for preventing an objectionable quantity of oil from being thrown into the lower end of the cylinder.

15. In a machine of the character de- 120 scribed, a crank case that is adapted to contain a bath of lubricating oil, a crank shaft journaled in bearings mounted in the end walls of the crank case, means for supplying 125 oil to said bearings, and means for causing any oil that escapes from the outer ends of said bearings to flow back to the crank case,

said means consisting of an inclined rib on the underside of one of the bearings that extends through a breather opening in the crank case and an oil pocket arranged at the 5 outer end of the other bearing that communicates with a duct that leads to said oil bath.

In testimony whereof I hereunto affix my signature in the presence of two witnesses, this 14th day of June, 1915.

GEORGE F. STEEDMAN.
